UPHOLSTERY FORMING APPARATUS

Clarence W. Avery, Detroit, Mich., assignor to
The Murray Corporation of America, a corpora-
tion of Delaware

Application December 15, 1937, Serial No. 179,845

4 Claims. (Cl. 112—2)

The present invention relates to upholstery forming apparatus and more particularly relates to that part of such apparatus in which fibrous material is formed and supplied to the machine for forming fibrous bats.

The primary object of the present invention is to provide a structure by which fibers, which are passed through processing machines, may be automatically returned to the supply line from selected stages in the machine in the event that other machines to which the fibers are fed are stopped.

Another object of the present invention is to provide a complete circuit, for the supply of fibrous material to processing machines, having a conduit associated with the circuit which has an inlet at an intermediate stage in the machines and an outlet communicating with the circuit, whereby the fibrous materials may be returned to the circuit from intermediate stages in their passage through the machine.

Other objects of the invention will become apparent from the following specification, the drawing relating thereto, and from the claims herein-
25 after set forth.

In the drawing in which like numerals are used to designate like parts in the several views throughout:

Figure 1 is a perspective, diagrammatic view
30 of apparatus embodying features of the present invention;

Fig. 2 is an enlarged fragmentary, perspective view, with parts broken away, illustrating a valve used in the embodiment of the invention shown
35 in Fig. 1; and

Fig. 3 is a fragmentary, perspective view of a portion of the apparatus illustrated in Fig. 1, illustrating a modified embodiment of the present invention.

One of the steps in the formation of upholstery articles is the processing of fibers which are fed to machines which form a felted bat. The bat is continuously formed and provides the padding for upholstery articles, and is thereafter combined with backing material and finish material which are sewed together and shaped to form the upholstery articles.

In processing the fibrous material, scrap material, such as cloth and burlap scrap, is fed into a feed hopper within which the materials are roughly shredded into the fibers. The fibers are thereafter drawn through a conduit by means of suction to the inlet end of a conveyor. The conveyor carries the fiber to discharge openings from
55 which the fibers are discharged into feed hop-

pers. Each of the feed hoppers thereafter supplies the fibers to a garnetting machine within which the fibers are further processed by combs and cutters. The fibers are then deposited upon conveyors which carry the fibers to a position above another continuously moving belt upon which the fibers are formed into a felted bat. As mentioned above, the bat is then carried through other machines to complete the upholstery article.

It frequently occurs that the machines which form the upholstery article are stopped for various periods of time; and when such machines are stopped the feed of the fibrous material to form the bat is no longer necessary. In prior machines, when such shut-down occurs, it is necessary to run the fibers completely through the garnetting machine and deposit the fibers on the bat forming conveyor where the fibers are collected and returned by hand to the inlet hopper along with the scrap material. This is a troublesome and expensive step due to the handling of the fibers and also due to the fact that the fibers which have been once processed are again passed through a portion of the apparatus with unnecessary processing steps being repeated thereon. There is also a considerable waste of time in operating the fiber processing machines as it is necessary to run the fibers completely through the machines to their discharge end before they can be conveniently gathered and returned.

According to the present invention, conduit means are provided which gather the fibers at an intermediate stage in the passage of the fibers through the processing machines; and the fibers are then returned to the supply conduit directly. This operation is automatic upon the shut-down of the upholstery forming machines; and during the shut-down the fibers circulate in the supply circuit so that upon resumption of operation of the machines, the fibers are again supplied to the garnetting machines.

Referring to the drawing, and referring particularly to Figs. 1 and 2 for a detailed description of the present invention, upholstery forming apparatus is generally indicated at 10. The particular arrangement of the upholstery forming element is merely illustrative as it will be evident that the present invention is capable of use with other types of apparatus. The apparatus indicated at 10 is substantially the same as that disclosed and claimed in the copending application of Alfred H. Haberstump, Serial No. 179,075, filed December 10, 1937; and in general includes bat forming mechanism 12, stitching mechanism 14, 55

severing mechanism 16, gathering mechanism 18, and a sewing machine 20. Reference may be had to the Haberstump application referred to for a more detailed description of the steps in the method and the apparatus used to perform such steps.

Garnetting machines are diagrammatically illustrated at 22, there being three such machines indicated, and these garnetting machines may 10 be of the type disclosed in the copending application of Clarence W. Avery Serial No. 58,859, filed January 13, 1936. These Garnetting machines provide the means for distributing a substantially homogeneous, uniform layer of non-woven, fibrous padding material upon the horizontal conveyor 12 of the bat forming mechanism. It will be understood by those skilled in the art 15 that other suitable means may be used for accomplishing the results desired in this connection, and that the machines shown merely illustrate one preferred method and apparatus for accomplishing this result. The garnetting machine 22 includes cutters and combs which process the fibrous materials fed thereto and distribute them at random substantially in a uniform, non-woven layer, as they are fed out of the machine 20 by means of an endless conveyor 24. The fibers are discharged from the conveyor 24 onto a continuous conveyor 26 which disposes the fibers 25 onto the horizontal conveyor 12.

Means are provided for supplying roughly matted fibrous material to the machines 22, which includes a supply bin 28 into which the scrap material such as cloth or burlap sacking 30 30 is charged. The scrap 30 is torn in the bin 28 into the form of rough, matted fibers. The roughly matted fibers are withdrawn from the bin 28 by means of suction into a supply bin 32, and outwardly from the supply bin 32 through a conduit member 34. The conduit 34 discharges into one leg 36 of a Y connection 38 and discharges therefrom into a supply conduit 40. Suction is applied to the conduit 40 by means of a suitably driven blower mechanism 42, through a 40 conduit 44, which communicates through a suitable valve 46 with the conduit 40. The valve 46 is of the usual construction used in the art and functions to permit the discharge of the fibrous material from the conduit 40 while suction is applied to the conduit 40 for carrying the fibrous material therethrough. The fibrous material is discharged from the valve 46 into a confining conduit 48, which has a continuously moving endless conveyor 50 forming the bottom thereof. 45 The fibrous material within the conduit 48 is thus carried along the conduit to discharge conduits 52, there being one for each of the machines 22, having automatically operable gates 54 associated therewith. When the gate 54 is opened, the fibrous material is caused to pass downwardly 50 through the conduit 52 into a hopper 56. The hopper 56 is operatively associated with its corresponding gate 54, as well understood in the art, so that when a predetermined amount of fibrous material is charged into the hopper 56, the gate 54 is automatically closed. Upon depletion of the material contained within the hopper 56, it automatically operates to open the gate 54 so that more fibrous material is then discharged 55 into that hopper. When all of the hoppers are filled so that none of the fibrous material is being discharged thereto, the fibrous material within the conduit 48 is caused to pass to the end of the conduit into an end conduit member 58 60 which discharges into a conduit pipe 60. The

conduit pipe 60 is in return communication with the inlet pipe 40 beyond the Y connection 48. This provides for recirculation of the fibrous material through the pipe 60 and the conduit 40 for return to the hoppers 56 in the event that the fibrous material is not used as fast as it is supplied; and also provides for the recirculation of the fibrous material so that it need not be returned to the beginning of the processing operation.

The fibrous material is discharged from the hoppers 56 into their respective machines 22, within which the fibers are further processed to the point of refinement required for forming the bats.

According to the present invention, upwardly directed return conduit members 62, having enlarged inlet nozzles 64, are disposed at an intermediate stage in the passage of the fibrous material to the bat receiving conveyor 12, and in the embodiment illustrated in Fig. 1 are disposed immediately above each of the conveyors 24. The conduit members 62 communicate with a common conduit member 66, which in turn communicates with the other leg 68 of the Y connection 38.

A two-way valve, generally indicated at 70, is interposed between the outlets and the conduits 34 and 66 and the inlets 36 and 68, respectively, of the Y connection 38. The valve 70 includes a valve housing 72 within which a movable valve member 74 is pivotally mounted. The valve member 74 includes a straight arm portion 76 which is keyed at substantially its center to a pivot shaft 78 for pivotal movement therewith. At diametrically opposed ends of the arm 76 are substantially circular closure members 78 and 80 which are adapted to close off the discharge ends of the conduits 34 and 36 respectively, depending upon the position of the valve member 74. The shaft 78 has a crank arm 82 connected thereto which in turn has a rod 84 pivotally connected thereto. The arm 84 is associated with a solenoid 86 which is connected by a lead 88 to an automatic switch 90, preferably located on the sewing machine 20.

In the embodiment illustrated in Fig. 3, the nozzles 64 are disposed above the bat receiving conveyor 12 and are associated with the lower end of the conveyor 26 above the conveyor 12. As disclosed in the copending Avery application mentioned above, the lower end of the conveyor 26 is adapted to reciprocate across the top of the conveyor 12; and in the embodiment illustrated in Fig. 3, the nozzles 64 are so arranged as to reciprocate with the conveyor 26. The nozzles 64 are connected by flexible conduits 92 with the common conduit 66 so as to permit such reciprocation, and are of course disposed closely adjacent to the top of the conveyor 12 so that the fibers deposited thereon may be readily collected and returned to the conduit 66. The remaining part of the apparatus for the structure illustrated in Fig. 3 is substantially the same and functions the same as the structure illustrated in Figs. 1 and 2.

In operation, when the mechanism 10 is operating to form the upholstery articles, the valve 74 is in such a position as to shut off the discharge end of the conveyor 66; and the discharge end of the conduit 34 is open for passage of the material into the conduits 36.

In case of shut-down of the mechanism 10, the sewing machine 20 stops and the switch 90 automatically actuates the magnetic switch 86 to shift the valve 74 to the position indicated in Fig. 2 so that the conduit 66 communicates with 75

the conduit 68, and the conduit 34 is shut off from communication with the conduit 36. The suction which is applied to the conduit 40 is then transmitted through the conduit 66 to the nozzle 64, and the fibrous material located immediately under the nozzle 64 is drawn into the conduit 66 and into the supply conduit 40. Upon resumption of operation of the machine 10, the switch 90 is again actuated to return the valve 74 to its initial position so that communication between the conduits 66 and 68 is blocked off and communication between the conduits 34 and 36 is resumed.

While the invention is illustrated with upholstery forming machines and has particular utility with such machines, it will be evident to those skilled in the art that the invention is capable of use with machines having other uses. Formal changes may be made in the specific embodiments of the invention described without departing from the spirit and substance of the invention, the scope of which is commensurate with the appended claims.

What is claimed is:

1. Apparatus of the class described including, in combination, fiber processing means having a portion thereof in which the fibers are exposed, machine means for receiving the fibers from the processing means and forming articles therewith, supply conduit means for supplying material to said processing means, means applying a vacuum to a portion of said supply conduit means for causing movement to material therethrough other conduit means having its inlet end disposed above the exposed portion of said processing means and having its outlet end connected to said supply conduit means, valve means controlling the communication between said other conduit means and said supply conduit means, and means automatically controlling actuation of the valve means in accordance with the operation of said machine means.

2. Apparatus of the class described including, in combination, fiber processing means having a portion thereof in which the fibers are exposed, machine means for receiving the fibers from the processing means and forming articles therewith, supply conduit means for supplying material to said processing means, means constantly applying a vacuum to a portion of said supply conduit

means for causing movement of the material therethrough, other conduit means having its inlet end disposed above the exposed portion of said processing means and having its outlet end connected to said supply conduit means, valve means controlling the communication between said other conduit means and said supply conduit means, and means automatically actuating said valve means in response to the operation of said machine means.

3. Apparatus of the class described including, in combination, fiber processing means having a portion thereof in which the fibers are exposed, machine means for receiving the fibers from the exposed portion of said processing means and forming articles therewith, supply conduit means for supplying material to said processing means, means constantly applying a vacuum to a portion of said conduit means for causing passage of said material therethrough, other conduit means having its inlet end disposed above the exposed portion of said processing means and having its outlet end connected to said supply conduit means, valve means controlling the communication between said other conduit means and said supply conduit means, and means automatically actuating said valve means in response to the operation of said machine means.

4. Apparatus of the class described including, in combination, fiber processing means having a portion thereof in which the fibers are exposed, machine means for receiving the fibers from the processing means and forming articles therewith, a conduit means forming a complete circuit for carrying the fibrous material therethrough, means applying a vacuum to a portion of said circuit to cause passage of said fibrous material therethrough, conduit means communicating said circuit means with said fiber processing means for supplying fibrous material to said processing means, other conduit means having its inlet end disposed above the exposed portion of said processing means and having its outlet end connected to said supply conduit means, a valve controlling the communication between said other conduit means and said circuit, and means automatically actuating said valve in response to operation of said machine means.
